DIRECTIONAL ARROW

Elmer H. Geissler, Atlanta, Ga.

Application July 31, 1952, Serial No. 20,866

Term of patent 7 years

(Cl. D72—1)

To all whom it may concern:

Be it known that I, Elmer H. Geissler, a citizen of the United States of America, residing in Atlanta, in the county of Fulton and State of Georgia, have invented a new, original, and ornamental Design for a Directional Arrow, of which the following is a specification, reference being had to the accompanying drawing, forming part thereof, and wherein:

Fig. 1 is a side elevational view of a directional arrow showing my new design;

Fig. 2 is a left end elevational view;

Fig. 3 is a right end elevational view; and

Fig. 4 is an elevational view of the top edge.

The side and edge of the directional arrow not shown are, respectively, the same as the side and edge shown.

I claim:

The ornamental design for a directional arrow, substantially as shown and described.

ELMER H. GEISSLER.
